Assistant Examiner—Robin V. Taylor[57] CLAIM

The ornamental design for a combined sock storage and washing bag, as shown and described.

DESCRIPTION

FIG. 1 is an exploded front elevational view of the combined sock storage and washing bag showing our new design; FIG. 2 is an exploded rear elevational view thereof; FIG. 3 is an exploded right side view thereof; FIG. 4 is an exploded left side view thereof; FIG. 5 is an exploded top plan view thereof; and, FIG. 6 is an exploded bottom plan view thereof. The broken line showing of a hanger and hooks is for illustrative purposes only and forms no part of the claimed design.
